18 Claims. (Cl. 118—11)

This invention relates to the production of lithographic printing plates and particularly to the coating of metal printing plates of this kind.

In the lithographic printing industry, many different kinds of metal printing plates are employed where the image to be printed is transferred to the lithographic plate by photographic processes, and with such metal printing plates, it is necessary that a photographically-sensitized coating be applied to the surface of the printing plate. Depending upon the particular kind of printing plate that is being produced, the thickness and drying characteristics of the photo-sensitive coating varies considerably, but in every instance, the quality of the final lithographic printing depends in a large measure upon the quality and uniformity characteristics of the photo-sensitive coating that has been applied. The photo-sensitive coating is considered to be of poor quality where it includes bubbles or foreign matter, and if such coating varies unduly from the desired uniform thickness in the working areas of the plate.

In the past such photo-sensitive coatings have been applied, in most instances, on a whirler which usually constitutes a horizontal table mounted for rotative movement about the vertical axis, and after the plate to be coated has been disposed in a centered relationship on the whirler table, the coating material has been poured manually onto the center of plate while it is rotated with the table. It is customary just prior to the application of the coating material to flush the plate surface with water to insure cleanliness of the surface that is to be coated, and after the coating material has been applied and has leveled off to a smooth surface so as to fully dry the coating before the plate is removed from the whirler.

In prior whirlers, great difficulty has been experienced in attaining even drying of the coated surface, and such whirlers have employed covers and drying air has been forced through the whirler along different paths. In an effort to attain more uniform drying, heating elements have in many instances been placed inside of the whirler, as for example on the inside surface of the cover, and this has been done in an effort to cause the center portions of the coated surface to dry at the same speed as the edges or corners of this surface. So far as I am aware, this expedient has not been successful except in those instances where an operator became particularly skilled in applying the heat for accurately determined periods.

In other instances, where the air has been heated before forcing the same into the whirler cabinet, but even where this expedient has been used, there has been a marked tendency for the edges or corners of the coating on a plate to dry ahead of the center portion. In all of the prior whirlers of which I am aware, there has been a marked tendency to circulate dust and dirt, including dry particles of coating, within the whirler cabinet so as to produce blemishes in the coated surface.

The prior coating procedures have required considerable time and manual labor in putting the plates in posi-

2

tion, applying the flushing water and the coating, and thereafter removing the coated plate from the whirler, and because of uneven drying and because the several operations have been performed manually, there has been a considerable loss due to lack of quality and uniformity in the coated plates.

In view of the foregoing it is the primary object of the present invention to enable greater uniformity and high quality of coating to be attained in lithographic printing plates, and objects related to the foregoing are to enable uniform drying of the coating to be attained, and to enable the handling and coating of the lithographic printing plates to be accomplished automatically and in such a manner that uniformity of coating is attained while assuring that the coating is free from bubbles and foreign matter.

Another and related object of this invention is to provide an improved whirler in which the drying-air is supplied in such a way that uniformity of drying is attained throughout the plate surface while at the same time avoiding circulation of dust or dirt that might mar the coated surface.

Other and more specific objects of the present invention are to simplify the handling of lithographic printing plates to enable the same to be handled by lifting engagement with the top surface thereof, both before and after the coating operation, and to enable this to be done without danger of damage to the coated surface.

Another important object of the present invention is to enable a whirler to be started and stopped automatically, to perform its coating and drying functions, and to be thereafter unloaded automatically so that there is no need for the plates to be handled individually.

Another object is to provide a whirler wherein the plate is fully covered and shielded from outside dirt and dust during the entire flushing, coating and drying operation, and a related object is to accomplish this in such a way that the plate is stopped in a predetermined position or relationship after the drying operation, thus to adapt the whirler for cooperation with an automatic plate handling and transporting mechanism.

Another important object of this invention is to provide a novel and advantageous drive arrangement for the whirler table so that the plates may be positioned loosely thereon and yet will not be displaced on the whirler table during the starting and stopping of the whirler table.

Another important object of the present invention is to provide a plate handling and transporting unit that is adapted to handle lithographic printing plates by lifting the same and then transporting the plates individually to different locations, and a related object is to provide for vacuum lifting of the plates in such a way that the lifting action is attained by one set of lifting devices prior to the coating operation, and by another set of lifting devices after the coating operation, thus to assure that the coating of the plates is not contaminated.

Another related object is to provide a plate lifting and transporting apparatus that is operable to lift plates from or to deposit plates on stacks of varying heights, and a related object is to accomplish this by control means of a simple, novel and advantageous character.

Another object of the present invention is to provide a plate lifting and transporting mechanism of the aforesaid character that may be operated automatically through a sequence of plate lifting, transporting and depositing operations so that the attention of an operator is not needed after a sequence of automatic handling and related operations has been initiated.

Other and further objects of the present invention will be apparent from the following description and claims and are illustrated in the accompanying drawings which

by way of illustration, show a preferred embodiment of the present invention and the principle thereof and what I now consider to be the best mode in which I have contemplated applying that principle. Other embodiments of the invention may be used and structural changes may be made as desired by those skilled in the art without departing from the present invention.

THE APPARATUS IN GENERAL

For purposes of disclosure the invention is herein illustrated as embodied in an automatic plate handling and coating installation 20 that comprises whirler 21 that has an automatic operating cycle in which lithographic plates P are flushed, coated and dried, and a plate handling and transporting unit 22 that is coordinated with the whirler 21 in its automatic operation so that the plate handling and transporting unit 22 is operable to pick up a lithographic plate P from a supply station I, transport the same to station IV at which the whirler 21 is located and deposit the plate P on the whirler, and after completion of an automatic sequence of flushing, coating and drying operation by the whirler 21, is operable to pick up the coated plate P and transport the same to station II of the plate handling unit 22 where the plate P is deposited on a stack of finished coated plates.

The plate P that is coated by the present apparatus may be any type of lithographic plate, usually of metal, whether the plate has a grained surface or an ungrained surface, and the plate may be made of a single layer of metal such as an aluminum or zinc plate, or may comprise two or more layers of metal as is the case in bi-metal and tri-metal plates.

THE WHIRLER 21

The Cabinet

The whirler 21 as shown in Figs. 1 to 6 of the drawings comprises a cabinet or housing 100 having a cylindrical vertical side wall 101 supported by a pair of front

legs 102 and a pair of spaced rear legs 103, and within the housing 100 a horizontal whirler table 105 is mounted for rotation on a vertical axis that is centered in the housing 100. The housing 100 has a top wall 106 that is spaced upwardly from the table 105 and in which a rectangular access opening 107 is provided through which the lithograph plates P may be put into position on the whirler table 105. The whirler table 105 preferably has a plurality of upstanding returning pins 105P spaced outwardly from the location of the edges of a plate that is in the normal centered plate location, and these pins are provided as a safety means so that in the event the plate P becomes displaced from its centered position, it will be held against excessive outward movement on the table.

The access opening 107 is slightly larger than the size of the largest plate that is to be coated with the whirler 21, and with this arrangement, it is possible to close the whirler during its operating cycle through the use of a tilted cover or lid 108 that is of a minimum size and weight. The lid 108 is rectangular in form and is arranged so that it may rest on an upward flange 107F that is provided about the access opening 107. The lid 108 is mounted for pivotal movement about an axis parallel to its major axis by the provision of supporting arms 108A that extend upwardly and rearwardly from the rear corners of the lid 108 as shown in Figs. 3 and 4 of the drawings. The rear ends of the arms 108A are pivoted by aligned pivots 108P on upward extensions 103E of the rear legs 103 so that the cover 108 may be moved from its closed position as shown in Figs. 1 to 3 to its open position that is shown in full lines in Fig. 6 and in dotted outline in Fig. 3.

The circulation of the drying air

The cover 108 is arranged in the present instance to provide a portion of an air supply passage through which drying air may be forced into the housing 100, and for this purpose, an elongated air discharge opening 108D is provided in the cover 108 so as to extend from one of the rear corners of the cover 108 to substantially the central point of the cover. This air discharge opening 108D is thus located so that air discharged therefrom will move downwardly so as to strike an area of the plate P between the central point of the plate and one edge of the whirler table 105. The air that is thus forced into the whirler cabinet through the discharge opening 108D strikes the whirling coated surface of the plate P at a considerable velocity and insofar as drying may be concerned, the effective velocity, or its velocity relative to rotating coated surface, varies from the center of the plate to the outside edge thereof. The air at the outside edge may be said to be required to dry a greater area of the plate, and while this would theoretically indicate the need for a greater air volume at the outer edges of the plate, I have discovered that by making the discharge opening 108D of substantially constant width from end to end, the relatively larger volume of air per unit of plate surface near the center acts to cause drying to progress in the central areas at a rate substantially the same as in the outer areas where the higher effective air velocity acts to dry the larger areas that are to be dried near the outer edges of the plate.

The drying air that is introduced into the cabinet through the openings 108D is, under the present invention, circulated within the cabinet in such a manner that it does not pick up dust and dirt that may be present within the cabinet, and in accomplishing this purpose it may be pointed out that the bottom of the cabinet 100 is closed except for a drain through which water and liquid coating material may pass. The air is discharged onto the upper surface of the plate and the table, and this is accomplished by providing air outlets about the periphery of the housing 100 and just below the top wall 106. Thus the top wall 106 is supported on a plurality of spaced

supports 106S that extend upwardly from the side wall 101, and between the supports 106S, air outlet passages 106D are provided. Thus the air that enters the housing through the opening 108D strikes the top of the table or the plate and may move outwardly over the plate and the table so as to escape from the housing through the opening 106D. Thus, in its entire path of movement through the housing 100, the air does not pass with any particular velocity to the bottom of the housing where it might tend to pick up dirt or particles of dry coating material and the like.

In practice I have discovered that the total area of the air escape openings 106D, and the location thereof in a circumferential direction relative to the inlet passage 108D has a bearing upon uniformity of drying. Considering that the table rotation imparts rotative motion in the same direction to the air, as indicated by the arrow in Fig. 4A, it may be pointed out that the best drying action is attained by blocking up a large proportion of openings 106D that are so chosen with respect to the inlet opening 108D, a large proportion of the drying air must travel almost 360° within the housing before it is discharged. In Fig. 4A, a typical arrangement of the discharge openings or outlet openings 106D has been diagrammatically illustrated, and those openings 106D that are blocked or closed are indicated by the letter B in Fig. 4A. In this arrangement some of the air may pass from the housing at several points along the rotative path, but the major portion discharges after it has traveled just slightly less than 360°. The total area of the effective openings 106D is just slightly less than the area of the opening 108D. With this arrangement of the discharge opening 108D and outlet openings 106D, it has been found that circulation of dust has been for all practical purposes limited, and the coating material dries uniformly on the plate P so that there are no evidences whatsoever of ridges or double coating near the edges or corners of the plates. On the upper surface of the cover 108, a duct 110 is provided which is arranged to discharge through the discharge opening 108D and which extends rearwardly to the rear edge of the cover 108 where the rear end of the duct 110 engages the forward end of a main air supply duct 111. This engagement or connection of the ducts 110 and 111 is of course broken when the cover 108 is raised to its open position, as will be evident particularly in Figs. 3 and 4 of the drawings, and yet when the cover 108 is returned to its closed position, the connection of the two ducts is re-established so that drying air may be forced through the ducts and into the housing 100 as will be described in some detail hereinafter.

Operation of the whirler cover

The cover 108 is urged to its closed position by gravity, and is arranged to be opened by means of a cable 112 that extends from a connection at the midpoint of the cover 108 upwardly and rearwardly and over a pulley 112P that is carried at the upper end of a supporting column 112C. This cable 112 extends downwardly along the column and then under the whirler 21 where the cable is connected to a piston of an air cylinder AC-108 that is governed and controlled as will be hereinafter described to raise and lower the cover 108 automatically in the operation of the whirler. Air is supplied to the cylinder AC-108 under control of a solenoid valve SV-108 of the combined cut-off and vent type. This valve is open when it is not energized, so that the cover 108 is held open, and when the cover is closed during the coating and drying periods, the valve is energized so as to vent the cylinder AC-108 and allow the cover 108 to close.

The swingable coating and flushing arms

Means are provided for applying flushing water and coating material to the plate P in the operation of the whirler 21, and in order to facilitate alternate use of the machine for applying coating of two different kinds,

such means are duplicated in the whirler, and specific description will be confined to one of such means. Thus, a pair of coating arms 115 and 115-1 are provided as shown particularly in Figs. 1, 4A and 5, and the specific structure of the arm 115 will be given hereinafter. Thus the arm 115 extends from and is fixed to a vertical shaft 116 that is disposed within the housing 100 and closely adjacent to the vertical wall 101 thereof so that by rotative movement of the shaft 116, the arm 115 may be moved between a retracted position adjacent the side wall 101, shown in full lines in Fig. 5, and an operating position wherein the end of the arm 115 is disposed over the center of the table, as shown in dotted lines in Fig. 5. The arm 115 is operated back and forth between these positions by means including an air cylinder AC-115 that has the piston rod 117 thereof connected to an arm 116A that is rigidly fixed to the lower end of the shaft 116. Spring means 115S normally urge the arm 115 to its outer or retracted position. The operating cylinder 20 AC-115 is actuated to project the arm 115 under control of a solenoid valve SV-115 in an air supply line, and this is done automatically as will be described.

The arm 115 has three pipes 115W, 115A and 115C mounted thereon so as to extend from the inside or remote end of the arm beyond the shaft 116 and through an access opening provided in the side wall 101 of the housing by eliminating one of the supports 106S to provide one long opening in the location that would otherwise constitute two openings 106S. The pipe 115C is arranged 30 to supply coating material and has a flexible supply hose 118C connected thereto which includes a filter 118F, while the line 115A constitutes an air line whereby controlling air may be applied to a control valve 120 that is carried on the inner end of the arm 115, and a flexible 35 supply hose 118A is connected to the extended end of the pipe 115A. The pipe 115W serves as a water supply line, and at its outer end, just outside of the housing 100 is connected to a flexible water supply line 118W.

The valve 120 that is located at the inside end of the 40 arm 115 is arranged to control the flow of coating material through the valve 120, and as shown herein, the valve 120 is of elongated cylindrical form with a casing 121 within which a piston-like control valve member 122 may be reciproacted. The valve member 122 is urged to a 45 normal position by a spring 123, and is arranged to be actuated in a right-hand direction as viewed in Fig. 5A to its alternate or other position by means including an air cylinder 124, the piston of which acts upon the valve member 122. The air line 115A is connected to one end 50 of the air cylinder 124 so that when pressure air is supplied through the line 115A, under control of a solenoid valve SV-118A, the valve member 122 will be shifted against the action of the spring 123 to its second position.

The valve casing 121 has an outlet spout or nozzle 55 125 upon the lower end of which a cap 125C is threaded so as to hold a strainer or screen 125S removably in position across the outlet spout 125. This screen is of extremely fine mesh, on the order of 70 to 200 mesh per inch, so that the screen acts not only to break up and 60 prevent passage of air bubbles that may be present in the coating material, but also to remove dust, dirt and the like that may be present in either the coating material or the water that is to pass into the valve 120.

The water supply line 115W is connected to the casing 65 121 in such a position that water may flow through the casing and the outlet spout or nozzle 125 when the valve member 122 is in the normal position in which it is shown in Fig. 5A. The coating supply pipe 115C is connected to the casing 121 so that when the valve member 122 is in its other or actuated position, the coating material may flow from the pipe 115C through the outlet 125 and, of course, at the same time the flow of water is cut off. It might be noted that the flow of coating material is governed only by the valve member 122, but 70 that the water flow is additionally governed by a solenoid

valve SV-115W that is included in the flexible water supply line 118W. The air supplied to the air cylinder 124 is controlled by a solenoid valve SA-115A that is included in supply line 118A, and this solenoid valve acts not only as a cutoff or control valve, but also serves to vent the air cylinder 124 when the valve is closed.

The whirler table drive

The whirler table 105 is mounted and supported on a rotatable vertical shaft 126 and is driven from a motor 127 by means including a friction-type variable speed mechanism 128 that has its output shaft connected to the shaft 126. The variable speed mechanism 128 is of the friction-type that is adjustable by means of an adjusting lever 128L so that it may vary from a zero output speed to a suitable maximum speed. In the operation of the present whirler, the speed of the whirler table 105 is varied gradually in starting and stopping so that there is a uniform acceleration and deceleration, and this is done so that the plate P may rest in a predetermined position on the table 105 without clamps or securing devices, thus to enable the plate P to be readily and easily put in place or removed from the whirler table 105 by automatic means. The speed varying lever 128L is operated between its zero position and its maximum position by means including an air cylinder AC-105 that is constantly urged to a zero speed position by air supplied at a reduced pressure through a line 105C to one end of the cylinder. The lever 128L is controlled as to speed of operation in both directions by means of a hydraulic check cylinder HC-105 that is connected through a common linkage 129 to the air cylinder AC-105 and the lever 128L. Air is supplied to the forward end of the air cylinder AC-105 through an air line 137B under control of a solenoid valve SV-105 of the combined cutoff and vent type.

When the whirler table 105 is stopped it is desirable that the plate P that is carried thereby be located in the same rotative position, thus to facilitate automatic handling of the plate and enable the finished plates P to be stacked in a substantially uniform stack by the automatic entering means 22. In the present instance, since the plates P are rectangular in character, provision is made for stopping the whirler table 105 in either one of two rotative relationships that are displaced 180° from each other. In accomplishing this positioning, the shaft has a locating plate 130 fixed thereon beneath the whirler table 105, and this plate has a pair of locating notches 130N at diametrically opposite points as indicated in Fig. 9. These notches 130N are adapted for cooperation with a locating plunger 131 that has a pointed end that is adapted either to ride on the circular outer edge of the plate 130 between the notches or to enter one or the other notches 130N. The locating plunger 131 is actuated by an air cylinder AC-131, the plunger 131 being formed as a part of the piston of this air cylinder. The plunger 131 is urged to a retracted position by a spring 131S, and when the plunger is to be rendered effective, air is supplied to the rear end of the cylinder AC-131 from a line 137A by operation of a solenoid valve SV-131. Thus, in the stopping or deceleration of the table 105 that is accomplished by the variable speed mechanism 128, the air cylinder AC-131 is operated to urge the plunger 131 toward the disc 130 when the rotative speed of the table 105 has been reduced substantially to zero. The solenoid valve SV-131 is operated at the proper time under control of a switch S-128 that is engaged and operated by the speed control lever 128L as this lever reaches its zero speed setting. The plunger 131 then moves radially into engagement with the edge surface of the disc 130, and when one of the notches 130W moves into alignment with the plunger 131, the plunger is actuated into the notch so as to stop the table 105 and locate the same in one of the two positions determined by the notch 130W. The table is thus stopped with a predetermined diameter thereof parallel to the major axis of the opening

107, and the plate P may be removed easily by vertical lifting thereof. As the plunger 131 moves into one of the notches, an abutment on the plunger engages and actuates a switch S-131 which serves as a controlling means for initiating further automatic operation of the system as will be described.

The coating supply means

The coating solution may be either a photo-sensitive solution or a simple gum solution for protecting the surface of the plate, and the two arms 115 and 115-1 may be allocated to two different coating materials that are to be used selectively. For purposes of disclosure it may be considered that a photo-sensitive coating material is fed from a supply container 135 that is preferably supported in an elevated position and which is connected to the flexible coating supply line 118C of the arm 115. The coating is fed under pressure from the supply container 135 and this is accomplished by closing the top of the container and supplying air thereto from a pressure air source 136 through the lines 137 and 138 and a pressure regulator 139. By adjustment of the pressure regulator, the feeding pressure may be adjusted as desired and this feeding pressure coupled with control of the feeding time within fairly accurate limits serves to determine the quantity of coating material that is fed onto each of the plates P that is to be coated.

Supply of drying air

The drying air that is supplied to the housing 100 through the ducts 110 and 111 is furnished by a blower 140, and the air supply passes through a rather elaborate duct work 141 which as diagrammatically indicated in Fig. 9 of the drawings, includes a filter 142, a heater 143 and a humidifier 144 so that efficient and uniform drying operations will be attained, and introduction of the dust or the like onto the coating surface of the plate P will be avoided.

The operation of the whirler 21 is controlled automatically by a whirler timer, the operation of which is initiated under control of the lifting and supporting unit 22 as will be described, and when the cycle of operations of the whirler has been completed, the completion of the opening movement of the cover 108 causes one of the arms 108H to engage and close a control switch S-108 that is mounted on the related one of the leg extensions 130E, and this closure of the switch S-108 is effective to again initiate operation of the lifting and supporting unit 22 so that the coated plate P is lifted from the whirler table 105 and is transported to station II where it is lowered and deposited upon a pile of finished coated plates.

55 THE LIFTING AND TRANSPORTING UNIT 22

In general

The lifting and supporting unit 22 comprises a square cabinet-like base 400 from the center of which a rotatively mounted column 401 projects upwardly, and a rigid frame 402 projects outwardly from the column 401 to support an outer mounting member 403 in a vertical position wherein it is parallel to the column 401. In the present instance, the frame 402 is formed by a pair of parallel arms 402U and 402L. On the outer face of the frame member 403 an air cylinder 405 is mounted in a vertical position with its piston rod 405R extending downwardly therefrom and carrying a horizontally positioned lifting head 408 at its lower end. The lifting head 408 comprises a horizontal wall 408W with a downwardly projecting outer flange 408F, and beneath the wall 408W two sets of suction cups 410W and 410D are mounted so that these sets of suction cups may be used selectively to engage and lift plates P as will be described.

The suction cups and selection thereof

The set of suction cups 410W is mounted in a fixed position, and all of the cups 410W of the set are connected together by pipes 411 to which a vacuum source is connected as will be described. The cups are relatively large, and are disposed in a rectangular pattern about 12 to 16 inches apart so that in lifting a plate P, the lifting forces applied by each cup are relatively small.

The suction cups 410D are mounted on the lower ends of the piston rods 412 that extend into the piston and cylinder devices 412C that are mounted above the wall 408W, and a spring 412S in each cylinder serves to urge the related cup 410D to an upper or retracted position shown in Fig. 8. The several suction cups 410D may be connected to a vacuum source by a pipe 413 and this connection is controlled as will be described. When it is desired to lower the suction cups 410D to an effective position shown in dotted outline in Fig. 8, air is supplied to an upper cylinder 412C through an air line 413A.

As above pointed out, the sets of vacuum cups 410D and 410W are adapted for selective use, and the cups 410D are raised and lowered under control of an air valve 415 while the sets of cups are therefore selectively associated with a vacuum source through a control valve 416. This control valve 416 has a medially located air inlet 413A extended from the pressure air source, and a slideable valve member 415M is slideable between two positions to connect the inlet selectively with a vent 415V or with the air cylinder 412C. Solenoids 415W and 415D at opposite ends of the casing may be energized selectively to shift the valve member 415M to one or the other of such positions.

The vacuum valve 416 has a medial inlet pipe 420 extended to the vacuum pump, and a valve member 416V is slideable between two positions to connect the line 420 selectively with the wet cups through line 411 or the dry cups through the line 413. Solenoids 416D and 416W at opposite ends of the valve may be selectively energized to shift the valve member 416M between such positions. The valves 415 and 416 and the several piston and cylinder devices 412C are connected by a cover member 408C. During operation of the unit 22 the vacuum line 420 is continuously connected to the vacuum source 419. When a plate P is to be dropped or released from the suction cups, this is accomplished by feeding pressure air from a line 421 into the vacuum line 120. The air for this purpose is controlled by a normally closed solenoid valve SV-421 of the simple cutoff type that is located in the air line 421. In the vacuum line 420, between the valves 416 and SV-421 a vacuum sensing switch S-420 is located and this switch functions in the automatic control of the unit 22 as will be described.

Actuation of the lifting head 408

The lifting head 408, being supported on the piston rod 405R may in some instances tend to rotate about the axis of the cylinder 405, and in the present instance, this is prevented by a pair of guide rods 422 that extend upwardly from the head 408 on opposite sides of the two arms 402U and 402L. These rods 422 are relatively light and have bracing members 422B connected thereto. The guide rods 422 serve to keep the longitudinal axis of the lifting head 408 in the plane of the frame 402.

The head 408 tends normally to move downwardly under the action of gravity, and when the head is to be moved upwardly, air is supplied to the lower end of the cylinder 405 through an air line 425.

When the head 408 reaches its upper position, a block 422B on one of the rods 421 contacts a control switch S-405 mounted on the arm 402U so as to close the switch, and this switch is utilized in the automatic control of the machine as will be described.

The air line 425 is connected through a stub line 425S to the pressure air source 136, and a solenoid valve SV-425 of the combined-shut-off and vent type is included in the stub line 425S. Between the cylinder 405 and the vacuum SV-425, the line 425 has a pressure sensing switch S-425 that is arranged to be normally open, and this switch is closed when the pressure in the cylinder 405 is reduced substantially to zero. This condition occurs when the lowering of the head 408 has been completed so that the effective suction cup rests upon a stack of plates P. The closure of the pressure sensing switch S-425 is utilized for automatic operation of the machine to cause release of a plate P in a dropping operation, the initiation of the upward or lifting movement of the head 408, or to cause lifting of the head 408 after a plate P has been effectually engaged by the vacuum cups in a lifting operation as will be described.

Rotative actuation of the column 401

The column 401 as hereinabove described, is arranged for rotative movement, but in the present instance, such rotation is limited to some extent by a supporting or stiffening frame 430 that extends upwardly from the base 400 and then outwardly at 430A to provide a bearing for the upper end of the column 401. The location of the frame 430 is best shown in Fig. 1 of the drawings and this location is such that lifting head 408 may be moved from the loading station I in a clockwise direction to stations II, III and finally into station IV where the frame 402 is located on the opposite side of the supporting or stiffening frame 430. It will be observed that in moving into station IV, where the whirler 21 is located, the lifting head moves in a clockwise direction, and this is taken into account in the positioning of the whirler 21 so that the lifting head 408 moves toward the open cover 108 and over the access opening 107, as will be evident in Fig. 6 of the drawings.

The rotative movements are applied to the column 401 by a reversible electric motor 432 which operates through a reduction-gear unit 433 to drive the vertically extended output shaft 434. On this output shaft a small sprocket 435 is mounted and is connected by means of a chain 436 to a relatively large sprocket 437 that is loosely mounted on the column 401 within the base 400. The sprocket 437 constitutes the driving element of a friction clutch, the other or driven element being in the form of a friction disc 438 that is splined on the column 401 and which is pressed downwardly by a spring 439 into frictional contact with the sprocket 437. This provides a factor of safety in the operation of the machine so that in the event of a collision of the lifting head 408 with other apparatus, the frictional drive will slip.

As the column 401 is rotated, means are effective to sense the rotative position of the column so as to indicate the position of the lifting head 408. Thus the column 401 has a radial switch operating arm 440 fixed thereto within the base 400, this arm being located in the plane of the supporting frame 402, and the arm 440 is arranged to actuate switches S-I, S-II, S-III and S-IV as the lifting head 408 is moved into the correspondingly identified positions or stations. These position-indicating switches are utilized as will hereinafter be described to control certain aspects of the automatic operation of the machine.

When the column 401 has been rotated to any selected position, it is accurately located and locked in this position by means of a locking plunger 445 that is operated by an air cylinder 445C so that the locking plunger may engage with any one of four equally spaced locking notches 445N that are formed in a locking disc 445D that is fixed on the column within the base 400.

The plunger 445 is urged toward a released position by a spring 445S, and when the plunger 445 is to be locked, air is supplied to the outer end of the cylinder 445 through an air line 446 that is extended from the

supply line 137. A solenoid valve SV-445 is included in the line 446 and this valve is of the combined cutoff and vent type. Between the valve SV-445 and the cylinder 445C, a pressure sensing switch S-445 is connected with the line 446 so that the sensed presence or absence of pressure in the cylinder 445C may function in the automatic control of the unit 22 as will be described.

OPERATION AND CONTROL

In the operation and control of the present installation, several timers are employed. The first of these timers may be termed a cycle timer 500 that is of the motor operated type driven by a motor 500M and having a plurality of cam operated switches CS-1 to CS-33 inclusive. These switches are of the double throw type, and in the present instance, the connections are made in most cases between the common terminal and the normally closed contacts of the respective switches, the switches being held open by the related cams, and being allowed to close at appropriate times in the cycle of operation of the timer 500.

The second timer is a coating solution timer 501 that is driven by a motor 501M and is utilized to govern the length of the period during which the coating material is fed from the arm 115 onto the plate that is being coated. A similar timer 501G is also provided and is used alternatively for timing the period of application of coating when the second coating arm 115-1 is employed.

The third timer is a whirler timer 502 and this timer is also motor driven by a motor 502M and functions to govern the length of the drying cycle.

Control for the unit 22

The aforesaid timers are arranged as will be described in detail hereinafter to cooperate with a control relay system and with the position-indicating switches S-I to S-IV in initiating rotative movement of the lifting and transporting device as required to any selected one of the several stations thereof, and in determining the proper direction of rotation of the column 401. This selection and control involves the use of a 2-way motor starting relay 510 that has one coil 510L which when energized, closes circuit to the motor 432 in such a manner as to cause left-hand or counterclockwise rotation of the column 401, while an operating coil 510R may be energized to cause rotation of the column 401 in a righthand or clockwise direction. The power source comprises lines L1, L2 and L3, and the output to the motor 432 is extended from the starting relay through the wires T1, T2 and T3 in a conventional manner. The relay also includes sets of interlocking contacts 511L and 511R that are effective, as will be described, to prevent simultaneous operation of the two operating coils of the starter.

Selection of direction of column rotation

The direction selecting means comprises a plurality of relays that are energized in accordance with the station to which the head 408 is to be moved, and this energization is controlled in part by the position-indicating switches S-I to S-IV, and in part by either the automatic selecting action of the timer 500 or by manually operable means.

Due to the nature of the lifting and transporting unit 22, it will be clear that when the head 408 is to be moved into station I from any other station, this will always require left-hand rotation, and in the same way, when the head is to be moved into station IV from any other station, this must always be accomplished by right-hand rotation of the column 401. As to selection of stations II and III, however, as the destination for the head 408, it is possible, depending upon the previous location of the head, that the movement required may be either in the right-hand or a left-hand direction. The relay system is effective to automatically determine the required direction of rotation under such circumstances.

Thus a relay I-L is provided for use in the selection of

station I, and a single relay IV-R is provided for use in selection of station IV as a destination. In contrast to this, two relays II-R and II-L are provided for use in selecting station II, and two relays III-R and III-L are provided for use in selecting station III as a destination. Finally, a relay II-RL and a relay III-RL are provided for use in connection with the selection of stations II and III respectively.

The relay I-L has a set of normally open holding contacts I-L-1 and a set of normally open control contacts I-L-2. The relays II-R, II-L, III-L and IV-R also have similar sets of holding and control contacts that are similarly identified with a prefix identifying the respective relays and a suffix identifying the corresponding contacts.

In the relay II-RL, three sets of normally open contacts II-L-1, II-RL-2 and II-RL-3 are provided, and three similar sets of normally open contacts are provided in the relay III-RL.

In providing the energizing circuits for the above described relays and the operating coils of the starter 510, circuit is extended from line wire L-2 by a wire 601 having branches extended to one terminal of the operating coils of all of such relays and the starter 510.

The other terminal of the starter coil 510R is connected through the interlock contacts 511L to a wire 650R and when the relay coil 510R is to be energized, circuit is extended from line wire L-1 to the wire 650R through the No. 2 or control contacts of one of the relays II-R, III-R or IV-R, as will be described in some detail hereinafter. Similarly, the other terminal of the operating coil 510L is connected through the interlock contacts 511R to a wire 650L and when the coil 510L is to be energized, circuit is extended from line wire L-1 to the wire 650L to the No. 2 or control contacts of one of the relays I-L, II-L and III-L.

The relays II-RL and III-RL are utilized in determining whether the right-hand or left-hand relay relating to station II or station III is to be actuated, and this determination is made by circuits that are extended through the relay contacts of these relays from the position-indicating switches S-1 to S-4.

The operation in respect to relays I-L and IV-R will however be first described. Initially, such operation will be considered as being initiated by manual selection rather than by automatic selection, there being four push button switches PB-1 to PB-4 allocated respectively to stations I to IV. In considering any particular station-selection problem, the present position of the head 408 must be taken into account, and as a first example it will be assumed that the head is at rest in station II, and that it is desired to have the head move in a left-hand or counterclockwise direction to station I. When this is to be done, the push button switch PB-1 is actuated and this results in the energization of relay I-L. Keeping in mind that one terminal of the operating coil of this relay is connected to the line L-2, the closure of switch PB-1 extends circuit from a wire 615 that is connected to line wire L-1 to a wire 610 that is extended to the other terminal of the operating coil of this relay. The operation of the relay of course closes the control contacts I-L-2 so that circuit is extended from a wire 652 that leads from line wire L-1, through a branch lead 652-I and the control contacts to the wire 650L.

The coil 510L of the starter is thus energized to cause rotation of the column 401 in a left-hand direction, and such movement continues so long as the holding contacts I-L-1 are kept closed. Thus, one of the holding contacts is connected by a branch lead to the wire 610, and the other of these control contacts is connected by a wire 603 to the normally open contact of the position indicating switch S-1. This switch is of the double-throw type with its column contact connected to the wire 15.

When the relay I-L is energized as above described,

the starter coil 510L will be energized so as to extend circuit to the motor 432 to rotate the column 401 in a left-hand or counterclockwise direction, and as an incident to connect to the motor circuit, the solenoid valve SV-445 is energized to release the V-lock. The energizing circuit for the valve SV-445 is provided by extending the wire T-3 to one terminal of the valve solenoid and by connecting the other terminal of the solenoid to the line wire L-2 by a wire 653. The rotation of the column 401 continues until the head 408 reaches station I, and at that time the switch S-1 is actuated by the arm 440 to break the running circuit that has been extended by the wire 603 through the holding contacts of the relay I-L. The relay I-L then drops out so that the motor 432 is de-energized, and this de-energizes the solenoid valve SV-445 so that the V-lock returns to its effective position and accurately locates the head 408 in station I.

The selection of station IV is accompanied in generally similar manner by actuating the push-button switch PB-4 which extends circuit to the other terminal of the relay IV-R in the following manner:

In establishing this circuit, the switch S-4 is utilized, and since the head 408 is in position I in the assumed example, circuit is extended from the wire 615 through the normally closed contact of the switch S-4 and a wire 609 to one contact of the switch PB-4. From the other contact of this switch a wire 614 is extended to the normally open contact of the switch S-108 which serves as a safety switch which is closed only when the whirler lid 108 is fully open. If the whirler lid is in effect open so that the switch S-108 is closed, circuit is extended by wire 614B to the other end or terminal of the coil of the relay IV-R, thus to energize this relay. When the relay is energized, circuit is extended from line I through the control contacts IV-R-2 of this relay to the wire 650R, thus to cause operation of the motor 432 to drive the column 401 in a right-hand or clockwise direction. The relay IV-R is held in its actuated condition by a holding circuit that extends from the wire 614B through the holding contacts IV-1 and a wire 609 to the normally closed contact of the switch S-4. Hence, when the head 408 has moved into station IV, the arm 440 actuates the switch S-4 so as to break the holding circuits which causes the head 408 to be stopped and located in station IV.

As to the selection of stations II and III, the selection circuits are somewhat different and will be described particularly with respect to the selection of station II. Thus, assuming that the head 408 is in station IV, the selection of station II is accomplished by actuation of the push-button switch PB-2. When this is done, circuit is extended from the wire 615 to a wire 611 which is extended to the other terminal of the operation coil of the relay II-RL so that this relay is energized, and it is through the contacts of the relay II-RL and the cooperating contacts of the switch S-1 to S-4 that a further selection is automatically made which determines whether the relay II-R or II-L is to be energized. Thus the energizing circuit for the relay II-R is extended by a wire 655 to one of the contacts II-RL-1, and from the other of these contacts a wire 602 is extended to the normally open contact of the switch S-1. Similarly, a wire 656 extends from the other terminal of the operating coil of the relay II-RL to one of the contacts II-RL-2 and also to one of the contacts II-RL-3. The other contact II-RL-2 is connected by a wire 606 to the normally open contact of the switch S-3, while the other of the contacts II-RL-3 is connected by a wire 608 to the normally open contact of the switch S-1.

Similarly, connections are provided to the relay contacts of the relay III-RL. Thus the relay II-RL has the other end of its operating coil connected by a wire 612 to one of the contacts of the push-button switch PB-3. The other terminal of the operating coil of the relay II-R

is connected by a wire 657 to one of the contacts III-RL-1 and also to one of the contacts II-RL-3. The other contact II-RL-3 is connected by a wire 602B to the wire 602, while the other contact III-RL-2 is connected by a wire 604 to the normally open contact of the switch S-2. The other terminal of the energizing coil of the relay III-L is connected by a wire III-7 to one of the contacts III-RL-3, the other of these contacts being connected by a wire 608B to the wire 608. The connections 10 that have thus been described constitute the selecting contacts that are necessary to determine the right-hand and left-hand characteristics of the movement to be imparted to the column 401, and additional circuits are provided from the relay II-R, II-L, III-R and III-L for energizing 15 the operating coils of the starter 510 selectively, and further circuits are provided for holding the operated relays until the selected station has been reached.

Thus the control contacts of the relays II-R and III-R are connected by the line 652 and the wire 650R so that 20 when one or the other of these two relays is energized, the operating coil 510R of the starter will be energized. Similarly, the control contacts of the release II-L and III-L are connected by the wire 652 and the wire 650L to energize the starter coil 510R when these two relays 25 are energized. The running circuit for these two relays is provided as follows:

The relay II-R has one of its contacts II-R-1 connected to the wire 655, while the contacts II-L-1 are connected to the wire 656, and the other contacts of these 30 two pairs are connected by a wire 658 and from the wire 658 a wire 605 is extended to the normally closed contact of the switch S-2. One of the contacts III-R-1 is connected to the wire 657 while one of the contacts III-L-1 is connected to the wire 657A, the other two contacts of 35 these sets are connected together by a wire 659. A wire 607 extends from the wire 659 to a normally closed contact of the switch S-3. It might be pointed out that the common contacts of all of the switches S-1 to S-3 are connected to line wire L-1 by wires 615.

40 With the relays connected as above described, actuation of the switch PB-3 while the head 408 is located in station III, causes the desired left-hand movement of the head 408 in the following manner:

The circuit is extended through the switch PB-3 from 45 the wire 615 to the wire 612 which of course causes operation of the relay III-RL, and such operation of this relay serves to select and cause energization of the relay III-L. Thus it will be observed that of the three sets of contacts of the relay III-L, the contacts III-RL-3 are 50 the only ones that are connected back to line 615. Thus, this set of contacts is connected by wires 608B and 608 to the normally open contact of the switch S-4, but since head 408 is at this time in station IV, a switch S-4 will be operated so that circuit will be extended to the lines 55 615. As to the other two sets of contacts in the relay III-RL, the contacts III-RL-1 are connected through the wire 602 to the normally open contact of the switch S-1 which of course will be open at this time, while the contacts III-RL-2 are connected through the wire 605 to the normally open contact of the switch S-2 which is also in its open relation. Hence it will be clear that 60 of the three possible circuits through the contacts of the relays III-RL, the position-indicating switches of the unit 22 determine that circuits shall be extended only to the relay III-L. When the relay III-L is energized circuit is extended to the starter coil 510L so that left-hand rotation of the column 401 will move the head forward from station IV to station III where the relay III-L will 65 be caused to drop out due to the opening of the normally closed contact of the switch S-3.

70 A similar selection and operation takes place when the push-button PB-2 is pushed so that the column 401 will be rotated in the proper direction to move the head from the position which it is then located to station II.

Vertical movements of the head 408

Additional control switches are provided, and one of these is an off-on control switch S-660 that may be used to connect the line L-2 to the terminal board 661 of the relay panel where a series of connected terminals 661T are energized from the line L-2 when the switch S-660 is closed.

In addition, a push-button switch PB-6 is provided for manually initiating the pickup operation of the head 408, and a push-button switch PB-5 is provided for initiating operation of the drop cycle of the head.

In carrying out the pickup and drop cycles several relays are included in the relay box. Thus a relay D-5 and D-6 are provided for functioning in the drop cycle of the machine, while a pickup control relay P-7 is provided for functioning in the pickup cycle. In addition, relays are provided for governing the shifting of the cups 410D and for governing the supply of vacuum to the two sets of cups. Thus a relay DC-8 functions when the dry cups 410D are to operate, while a relay WC-9 functions when the cups 410W are to operate, and the operation of the relays DC-8 and WC-9 is interrelated with the rotative position of the head 408 as to insure the use of the proper cups according to the method of use to which the lifting and supporting device is to be put. All of these relays embody control contacts as will be described.

Pick-up operation of head 408

Thus, when a pick-up operation of the head 408 is to be initiated the manual pickup switch PB-6 may be actuated and this closes an energizing circuit for the relay P-7. This energizing circuit is extended from a terminal 15A by a wire 663 to one end of the coils of the relay P-7 and a wire 664 extends from the other end of this coil to a terminal T-20. Closure of the switch PB-6 has extended circuit to a terminal 21 so that circuit is further extended by a wire 665 to the normally closed contact of the vacuum sensing switch S-420, the common contact of which is connected by a wire 666 to a terminal T-1 which is connected to line wire L-2. This serves to energize the pickup relay P-7, and when this is done a holding circuit is closed through a normally open contact P-7-1 of this relay to the terminal T-21. Thus the relay P-7 will be held in its energized position until the establishment of a vacuum at the effective cups has closed the switch S-420 to be operated, and when this takes place the holding circuit will be broken and the relay P-7 will be energized.

The relay P-7 also provides a control circuit which is effective to release the air pressure in the lifting cylinder 405. Thus this control circuit is provided by normally open contacts P-7-1, one of which is connected to the wire 663 and the other of which is connected to a wire 668 that extends to a terminal T-22. From the terminal T-22 a wire 69 extends to one terminal of the solenoid valve SV-425, the other terminal of which is connected by a wire 670 to the normally open contact valve, the pressure sensing switch S-445 which is associated with the air lock device. The common terminal of the switch S-445 is connected by a wire 671 to the wire 666, thus to extend circuit to the line wire L-2. This circuit will thus be closed only when the locking piston is effective, and because the lifting piston 405 is being vented, the head 408 will move gradually downwardly at a speed depending upon the size of the vent that has been opened. The downward movement of the head 408 will continue until the head comes to rest, and this normally occurs when effective suction cups come into contact with a plate P that is to be lifted. The vacuum pump is then effective to build-up a vacuum at the effective cups, and when this vacuum has reached a predetermined amount, the switch S-420 is operated so as to break the holding circuit of the relay P-7. The valve SV-425 is therefore de-energized and air is again supplied to the lifting cylinder 405 so that the head 408 will return to its upper position, and the desired rotative movement of the column 401 may then be initiated as described hereinbefore.

Dropping cycle of the head 408

When the head 408 is to be moved through a dropping cycle, this may be initiated by actuation of the drop switch PB-5 which is connected across terminals T-18 and T-19 of the panel. This establishes an energizing circuit for the drop relays D-5 and D-6. Thus wires 673 and 673A are extended from the terminal T-15A to one end of each of the coils of the relays D-5 and D-6. The other ends of these coils are connected by a wire 674 to the terminal T-17. Closure of the switch PB-5 has, of course, connected these two terminals and circuit is extended from the terminal T-18 through a wire 675 to the normally open contact of the vacuum sensing S-420 which at this time would be closed due to the pressure of a plate across the vacuum cups. Circuit would thus be extended by the wire 666 to the line wire L-2 so that both of the relays D-5 and D-6 would be energized. When the relays D-5 and D-6 are energized a holding circuit is provided by relay contacts D-5-L, one of these contacts being connected to the wire 674 and the other of these contacts being connected by a wire 677 to the terminal T-18. This holding circuit will thus maintain the relays D-5 and D-6 energized until such time as the vacuum at the cups has been released so as to cause the sensing switch S-420 to return to its normal condition which serves to break the holding circuit of the relays D-5 and D-6.

The relay D-5, when energized, serves to govern the lift cylinder 405 through relay contacts D-5-2, one of which is connected to the wire 673 and the other of which is connected by a wire 668A to the wire 668. This circuit extends through the solenoid valve SV-425 and the sensing switch S-445 so that if the column 401 is locked, the air from the cylinder 405 will be vented so as to lower the head 408.

The relay D-6 provides a control circuit which is effective to release the vacuum at the cups and to maintain the vacuum released for a predetermined period so as to insure release of the plate from the cups. This control circuit extends from the terminals 15A by a wire 675A to one terminal of the air control valve SV-421 and from the other terminal of this valve a wire 676A extends to the terminal T-19 from which a wire 676B extends to the normal open contact of the relay D-6. The other or common contact of this relay is connected by a wire 677 to the terminal T-23. A wire 678 extends from the terminal T-23 to the normally closed contact of the air pressure sensing switch S-425, the common contact of which is connected by a wire 679 to the wire 666 so as to extend the circuit back to line L-2.

The circuit that has just been described is not closed immediately but is merely conditioned through the pressure sensing switch S-425, and when the air pressure in the lift cylinder 405 reaches zero, the switch is closed so that the air cylinder 421 is actuated, thereby to feed pressure air into the vacuum line for releasing the vacuum and dropping the plate P from the vacuum cups.

This circuit is maintained for a predetermined time through operation of a timer 505 that has a relatively short time period on the order of six seconds during which the energizing circuit to the air control solenoid SV-421 is maintained even though the relay D-6 becomes de-energized. Thus the timer 505 has wires 506 and 507 extended therefrom to the terminal T-15 and the terminal T-1 respectively, thus to be connected to the two line wires, and the wire 506 is connected directly to the timer motor. This establishes a connection to line wire L-1, and the timer 505 is started by a circuit extended through a wire 508 that is connected to the terminal T-19. The terminal T-19, of course, is initially

connected to the line wire L-2, and after the motor is started a switch 505S thereof is closed for the pre-determined timer period to connect the wire 507 to the other side of the motor circuit. Thus, the insertion of the pressure air to the vacuum system is continued for the time period to insure dropping of the plate P.

Selection of suction cups 410W or 410D

It has been pointed out hereinbefore that the dry suction cups 410D and the wet suction cups 410W are used selectively to insure that proper selection of cups is attained, and to insure proper connection of the vacuum line to the selected cups, and to do this the valves 415 and 416 must be actuated. This is done under control of the relays DC-8 and WC-9 in cooperation with the rotative position of the column 401 as such rotative position is indicated by the switches S-1 to S-4.

In accomplishing this the relays DC-8 and WC-9 are both operated each time the pick-up relay P-7 is operated. Thus the wire 664 has a branch 664A that is connected to one end of each of the coils of the relays DC-8 and WC-9, while the other terminals of these relay coils are connected by a wire 680 to the terminal T-15A. The common relay contact of the relay DC-8 is connected by a wire 681 to terminal T-25, while the common contact of the relay WC-9 is connected by a wire 682 to the terminal T-24. The normally open contact of the relay DC-8 is connected by a wire 683 to the wire 608 which extends to the normally open contact of the switch S-4 so that this side of the control circuit of the relay WC-9 can be completed only when the head 408 is at station I. It is at such a time that the use of the wet cups is to be desired.

As to the other side of the control circuit of these two relays, a wire 685 extends from the terminal T-25 and is branched for connection to one terminal of each of the solenoids 415D and 416D, the other terminals of which are connected by wires 686 to line wire L-2. Similarly, the other contact of the control circuit of the relay WC-9 has its circuit extended from the terminal T-24 by a wire 687 to one terminal of each of the solenoid 415W and 416W, the other terminals of which are connected by wires 688 to line wire L-2. Hence when a pickup operation is initiated in station I, the wet cups 410W are rendered effective, while such a pickup in station IV causes the dry cups 410D to be rendered effective.

Cycle timer relay R-10

The relay panel also includes a cycle timer relay R-10 that accomplishes two functions, one of which is concerned with the manual operation or selection and the other of which is concerned with the automatic operation of the machine. The relay R-10 has its operating coil connected across the wires T-1 and T-2 that energize the motor 432 so that the relay R-10 is energized whenever this motor is operated. The relay R-10 has a pair of normally closed contacts, one of which is connected by a wire 690 to the terminal 661T so that it represents line wire L-2. The other of these contacts is connected by a wire 691 to the terminal T-26. As will be described hereinafter, this terminal 26 has its circuit extended to form a part of the running circuit of the operating motor 500M of the timer 500.

The relay R-10 also has a pair of contacts, one of which is connected by a wire 692 to line wire L-1, and the other one of these contacts which is the normally closed contact is connected by a wire 693 to the terminal T-15A. This establishes a normal connection from the line wire L-1 to the terminal T-15A, but this connection is broken when the motor 432 is being operated and by breaking the circuit to terminal T-15A, all of the manual control circuits that originate at this terminal are disabled when the column 401 is being rotated. Thus the manual drop circuit and the pickup circuits are disabled under such circumstances.

AUTOMATIC OPERATION

As hereinabove pointed out, the cycle timer 500 serves as the primary control during operation of the entire system, and in association with the timer 500, a terminal board 700 is provided having terminals 701 to 728 so arranged that opposed terminals are connected. The timer motor 500M is operated in such a way that after it has been manually started, it has a running circuit that may be interrupted to stop the timer while certain of the automatic operations are being performed, and whereby this circuit may finally be broken at the end of the complete cycle of operation of the timer 500.

Thus, the terminal 701 represents line L-1, and is connected by a wire 730 to the common contact of the cam switch CS-28 of the timer, and from the normally closed contact of this switch a wire 731 extends to a terminal T-731. This circuit to line wire L-1 is utilized in running the timer 500 through an idle or run-out period during the drying cycle as will be described. It is from this terminal T-731 that one side of the circuit to the motor 500M is extended and this terminal is connected to line wire L-1 by a wire 731B through the normally closed contacts of a disabling relay 502R.

The starter circuit for the motor 500M is provided by means including a relay 732 the operating coil of which has one terminal extended to a terminal T-732 from which a wire 733 extends to the terminal 702 which represents line wire L-2. A terminal T-724 is connected by a wire 734 to the other terminal of the operating coil of the relay 732, and a wire 735 extends from the terminal T-724 to the terminal 724. A wire 736 including a manual starter switch 737 is extended to the terminal 701 so that by the closing starter switch 737, the relay 732 may be operated.

The relay 732 is energized through the manual start switch 737, and when the relay is thus energized it closes normally open sets of contacts 732-1 and 732-2. The contacts 732-1 constitute the holding contacts of this relay and are connected respectively to the wire 734 and to the normally open contact of the cam switch CS-33. Thus when the timer is in its stopped relation at the end of its cycle, the normally open contact of the switch CS-33 is closed and the common contact is connected by a wire 740 to the terminal T-731 so that the holding circuit is established upon operation of the relay. The wire 740 is also connected by a wire 741 to one of the normally open contacts 732-2 which constitute temporary running contacts functioning in one side of the motor circuit until the cam switch CS-33 assumes control. The other one of these running contacts is connected by wire 742 to one terminal of the motor 500M, while another wire 743 connects this contact to the normally closed contact of the cam switch CS-33. Thus when the relay 732 is operated, a holding circuit is established, and circuit is established from the line wire L-1 through the temporary running contacts of this relay to one terminal of the motor. Also, there is a holding circuit which is initially established through the normally open contact of the cam switch CS-33 which is then closed, but which is opened at the same time that the other or normally closed contact of switch CS-33 is closed, so as to thereafter provide a running circuit through the wires 742 and 743, and which is continued throughout the cycle. Opening of this circuit by the cam switch CS-33 terminates the timer operation at the end of its cycle. At the time that the running circuit is established by the cam switch CS-33, the holding circuit for the relay 732 is broken so that this relay drops out.

It will be noted that the motor circuit to the terminal T-731 extends through the normally closed contacts of the disabling relay 502R, and this disabling relay is arranged to be operated when the drying cycle is started, the cycle-timer 500 will be stopped, and when the drying cycle is completed, the timer 500 will be restarted. For this reason the energizing coil of the relay 502R is connected by

wire 745 in a circuit that is closed during operation of the timer 502.

In connection with such control of the cycle timer 500 by the drying timer 502 it should be pointed out that during the drying cycle, the cycle timer 500 is actually operated through an idle period which serves to run out a portion of the available time cycle of the cycle timer 500, thus, to enable the last operation of the mechanism to be initiated near the end of the complete cycle of the timer 550. Thus it is possible to reduce the running time of the timer 500 after initiation of the final operation of a cycle. Such idle running of the timer is accomplished by a cam switch CS-28 which as above pointed out, is connected to the line wire and when closed, serves to extend circuit to the terminal T-731. Such circuit thus provides a shunt around the disabling relay 502R. The cam switch CS-28 is arranged to be closed soon after the initiation of the drying cycle and to be maintained closed for a time period such that the remaining available timing operation of the timer 500 is just slightly more than sufficient to govern the automatic operations that are to take place after the conclusion of the drying cycle. This idle operation of the cycle timer 500 has been indicated in the timing diagram of Fig. 13.

The other side of the motor circuit of the motor 500M is extended to line wire L-2 and includes further disabling means so that motor 500M is stopped in response to rotative movement of the column 401 and also in response to downward displacement of the head 408. Thus, the other side of the motor circuit for the motor 500M is extended from its other terminal by wire 748 to the terminal 725, and a wire 749 extends this circuit to one of a pair of normally closed contacts of a disabling relay 750. The normally closed contact of this pair is connected by a wire 751 to the terminal 726 which is connected by a wire 752 to the terminal T-26.

The disabling relay 750 has one terminal of its operating coil connected to line wire L-2 while wire 753 extends to the other end of the side of the normally closed contact of the switch S-405, the common contact of which is connected by a wire 754 to line wire L-1. Thus, when the head 408 is in its upper position so that the switch S-405 is actuated, the line circuit for the disabling relay 750 is broken, but when the head 408 moves downwardly the switch S-405 assumes its normally closed position so that the relay 750 is energized and remains energized until the head 408 returns to its upper position.

Thus the running circuit for the cycle timer motor 500M is automatically broken during rotation of the column 401 and during pickup and drop operations of the head 408.

Control connections for the cam switches

As above pointed out, the automatic cycle of operation of the present installation is governed primarily by the timer 500, but the control of the cycle-timer 500 is superseded during the performance of certain of the functions that are involved. The automatic control that is exercised by the cycle-timer 500 is attained in certain respects by connecting selected cam switches of this timer in parallel, across corresponding manual control switches that have been described hereinabove. Since certain of these functions are repeated during the machine cycle, but at different times in such cycle, two or more of the cam switches that operate at different times in the cycle are connected in parallel across certain of the manual control switches as will be described.

Automatic pickup

Thus, the switches CL-1, CS-14 and CS-20 are allocated respectively to the initiation of the pickup function at stations I, IV and III, and it may be pointed out in the present instance, that in practice the pickup function in station III is not used, and while connections to the switch CS-20 have been shown, this has been done

merely for illustration and actually these connections are removed in the performance of the typical cycle that is described.

As to the switches CS-1, CS-14 and CS-20, the wires 620A are extended from the common contacts of these switches to the terminal T-20. Similarly, wires 621A are extended from the normally closed contacts of the cam switches CS-1, CS-14 and CS-20 to the terminal 721 and a wire 721A extends from this terminal to the terminal T-21. Thus the parallel circuits across the manual pickup switch PB-6 are provided.

Automatic drop

The initiation of the drop function has been allocated in 15 the present instance to cam switches CS-3, CS-16 and CS-22 that are each adapted to initiate the drop function at different times in the cycle at stations II, III and IV, it being noted that the second dropping operation at station II is not used in the present instance, and has 20 been shown merely for illustrative purposes.

Thus the common contacts of the switches CS-3, CS-16 and CS-22 are connected by wire 617A to the terminal 717 from which a wire 717A is extended to the terminal T-17. The normally closed contacts of these 25 three switches are connected by wire 618A to the terminal 718 from which a wire 718A is extended to terminal T-18. Thus, all of the cam switches CS-3, CS-16 and CS-22 are connected in parallel across the manual drop switch PB-5.

Automatic station selection

As to the automatic station selection for the unit 22 under control of the cycle timer 500, a generally similar 35 association of the cam switches with the previously described manually controlled selection circuit is followed with the exception, however, that the selection of station IV is rendered dependent upon the cover 108 of the whirler being fully open.

In the automatic cycle that has been described, a 40 single one of the cam switches is allocated to the selection of station I and thus, the cam switch 29 has its common contact connected by a wire 603A to the terminal 703 and a wire 703A is extended from this terminal to a wire 603, while the normally closed contact of the cam switch C-29 is connected by a wire 610A to the terminal 710 from which a wire 710A is extended to the wire 610. Thus, the cam switch CS-29 is connected in parallel across the push button switch PB-1, and when this cam switch is closed the selecting 45 circuits are operated to close the head 408 to be moved to station I.

Cam switches CS-15 and CS-21 are allocated to the 50 automatic selection of station II, although it may be pointed out that the switch CS-21 is not used in the cycle of operation that has been described, and is therefore disconnected in practice. Thus, the common terminals of the cam switches CS-15 and CS-21 are connected by wires 615A to the normally closed contact of the other set of normally closed contacts of the disabling relay 750, the other contact of this set being connected by a wire 615C to the terminal 715. Such connection through the disabling relay is employed as a further safety measure to guard against column rotation 55 while the head 408 is in a lowered position. The terminal 715 is connected by a wire 715A to the wire 692 which is of course connected to line wire L-1. This connection through normally closed contacts of the disabling relay 750 serves to disable the cam switches when the head 60 408 is out of its upper position. The normally closed contacts of the cam switches CS-15 and CS-21 are connected by wires 611A to the terminal 711 from which a wire 711A extends to the wire 611. These cam switches are thus placed in parallel across the manual selecting 65 switch PB-2 and will produce similar operation.

The cam switches CS-4 and CS-19 are allocated to the selection of station III, although the cam switch CS-19 is not used in the presently described cycle and is, therefore, disconnected. These switches are connected parallel across the switch PB-3, the common contacts thereof being connected to the wire 615A, while the normally closed contacts thereof are connected by a wire 612A to the terminal 712 from which a wire 712A extends to the wire 612. Thus, the switches CS-4 and CS-19 will produce the desired selection of station III.

As to the selection of station IV, the cam switches CS-2 and CS-13 are employed respectively when the whirler is to be loaded and when it is to be unloaded. The common contacts of these switches are connected by wires 609A to the terminal 709, and the wire 709A extends from this terminal to the wire 609. The normally closed contacts of the cam switch CS-2 and CS-13 are connected by wires 614A to the terminal 714, and a wire 714A extends to the wire 614. In this respect, it will be observed that this extends the circuit through the normally open contact of the switch S-108 so that the circuit is completed only when the whirler lid 108 has been opened so as to actuate and thus close the switch 108.

Starting and closing of whirler

After a plate has been put in position on the whirler table and the head 403 has returned to station III, the rotative movement of the whirler table is initiated under control of the cam switch CS-5. The common contact of this switch is connected by a wire 730A to the wire 730 which extends from line wire L-1, while a wire 627A extends from the normally closed contact of this cam switch to the terminal 727. It might be noted that cam switch CS-17 is also allocated to the same function, but is not used except when the second coating arm 115-1 is being employed, and therefore, in the example described herein, the cam switch CS-17 is disconnected. The circuit is extended from the terminal 727 by wire 727A to terminal 827 in a motor starter 127S that is associated with the whirler motor 127. The starter is arranged to connect lines L-1 and L-3 to lines TT-1 and TT-3 that extend to the motor 127, and the starter includes additional contacts 760 that are included in a holding circuit for the relay as will be described. Circuit is extended from terminal 827 by a wire 761 to one end of the operating coil of the starter relay, the other end of this coil being connected to line II. The holding circuit is provided by connecting the relay contacts 760 to the wire 761 and by connecting the other side of these contacts by a wire 763 to one terminal of the switch S-131. The other contact of this switch is connected by a wire 764 to a terminal 801 in the starter relay box and this relay is connected by a wire 765 to line wire L-1. Thus, the holding circuit for the starter relay 127S will be established as soon as the locking piston 131 of the whirler table has been withdrawn, and will be maintained until the locking plunger 131 has returned to its locking position at the end of the whirling cycle.

When the whirler motor 127 is energized, the movement of the lid or cover 108 toward its closed position is started, and to accomplish this, line wires TT-1 and TT-2 are also connected to the solenoid valve SV-108.

At the same time that the whirler motor relay 127S is operated, the speed control lever 128L is started on its control movement between its zero position and its maximum position. This is done by energizing the solenoid valve SV-105. Thus, one side or terminal of the valve SV-105 is connected to terminal 802 which is in turn connected by a wire 768 to line wire L-2, then one terminal of the valve SV-108 is connected to terminal 816 which is connected by a wire 716A to the terminal 716 of the timer 500. A wire 616A connects the terminal

716 to the normally closed contact of cam switch CS-12, and the common contact of this switch is connected to the wire 730 so as to be thus connected to line wire L-1. Thus the speed control lever is started toward its maximum position, and in the initial portion of this movement, it releases the switch S-128 so that it may assume its normal open condition. This is effective to release air from the lock cylinder AC-131, the control valve SV-131 of which is normally held open while the table is stopped. 10 Thus one terminal of the solenoid valve SV-131 is connected by a wire 770 to the terminal 802 of the whirler starter relay box while the other terminal is connected through the terminal 832 by wires 771 and 772 to one contact of the switch S-128, the other terminal of which 15 is connected to the terminal 801. Hence when the speed control lever allows the switch S-128 to assume its open position, the valve SV-131 is de-energized and the lock plunger 131 is retracted. As the lock plunger 131 is retracted the switch S-131 assumes its normal closed position so that the above described holding circuit is completed for the starter 127S.

Flushing and coating

When the table is thus started, or soon thereafter, the timer 500 initiates the outward swinging movement of the coating arm 115 as well as the flow of water to the discharge nozzle of the arm, and also initiates operation of the coating timer 501. Thus, the cam switch CS-7 initiates the outward swinging movement of the coating arm 115, and this cam switch is arranged to be closed for a period substantially longer than the maximum time required for the coating operation, the inward or return swinging movement of the arm being governed by the timer 501, as will be described. 35 It has been pointed out that the coating arms 115 and 115-1 may be used selectively, although in the present description the operation as to the coating arm 115 will be described in detail. Thus, two sets of controls are employed and may be rendered effective selectively by a switch 775. This switch is connected inside to the line wire L-1 by a wire 776, and in one position it extends circuit to a wire 728 and in another position to wire 723. The wire 723 is associated with the cam switch controls for use when the coating arm 115-1 is being used, and these connections will not be described herein, particularly since they are similar to connections from the wire 728 that are used when the coating arm 115 is employed. 40 Thus the cam switch CS-7 has its common contact connected to the wire 728 and its normally closed contact is connected by a wire 605A to one of a pair of normally open contacts of a control relay 780, the other of the contacts of which is connected by a wire 605B to the terminal 705, a wire 705A being extended from this terminal to a terminal 805 in the whirler starter relay box. A wire 805A extends from the terminal 805 to one terminal of the solenoid valve SV-115, the other terminal of this valve being connected to terminal 802. Thus when the cam switch CS-7 is closed, the arm 115 45 will be moved outwardly and it should be noted that the control circuit extends through the control relay 780 so that it may be broken by energizing the relay 780 when the coating arm 115 is to be returned to its normal outer position. This control is exercised by the timer 501. 50

The coating timer 501 has its operation initiated by the cam switch CS-8, the common terminal of which is connected to the wire 728. The other or normally closed terminal of this switch is connected by a wire 781 that extends to one terminal of the motor 501M, and to the common contacts of control switches 501-1 and 501-2 that are diagrammatically shown as being embodied in this timer. The other terminal of the motor 501M is connected by a wire 782 to terminal 702 which constitutes line wire L-2. The closure of the cam switch

CS-8 is extended for a period substantially that is great enough to allow the timer to function, and when the switch CS-8 is thus closed, circuit is extended through the normally closed switch 501-2 through a wire 606A to the terminal 706. The operating cam of the switch 501-2 allows this switch to have the desired time period during which coating solution is to be fed to the arm 115. The circuit is extended from the terminal 706 by a wire 706A to the terminal 806 from which a wire 806B extends to one terminal of the coating control valve SV-115A. This operates the valve member 28 so as to connect the coating line 115C with the discharge nozzle 125 of the coating arm 115, while at the same time closing the water line.

When the coating period has been completed, the switch 502-2 is opened and the valve member 28 returns to its normal position so as to stop the flow of coating material.

The switch 501-1 is arranged to control the return of the coating arm to its normal position, thus the contacts 501-1 are connected respectively to the wire 781 and through a wire 619A which extends circuit through a wire 619B to one end of the operating coil of the control relay 780, the other end of this coil being connected by a wire 619C to the wire 782. Hence, when the contacts 501-1 are closed at the end of the coating cycle the relay 780 is energized so as to break the circuit to the valve SV-115. The coating arm 115 thus returns to its normal operation position.

It has been pointed out that the nozzle 125 is flushed prior to the flow of the coating material therethrough, and this is governed by the cam switch CS-9, the common terminal of which is connected to the wire 723. The other or normally closed contact of this switch is connected by a wire 607A to the terminal 707 from which a wire 707A extends to the terminal 807, and a wire 807A extends from this terminal to one terminal of the solenoid valve SV-113W. Thus, during closure of the cam switch CS-9, the water is supplied to the coating arm. The switch CS-9 is closed for a period such that the water is turned off prior to the return of the valve member 28 to its normal position.

It has also been pointed out that a flushing operation is performed just before the arm 115 moves from its normal position and hence the cam switch CS-9 closes before such movement of the arm is started, and water flow continues until a short time after the nozzle of the arm 115 has reached its position over the center of the plate. Thus the nozzle is first flushed, then the plate itself is flushed, and finally when the coating line is connected, the coating material is applied. Furthermore, a second nozzle flushing operation takes place at a later time under control of cam nozzle-switch CS-23 which is connected parallel across cam switch CS-23 and which operates a short time after the arm 115 has returned to its normal position to again flush the nozzle and thus assure that coating material in the nozzle and the screen will be removed before it has hardened.

After the coating has been applied, the drying cycle is instituted and this is controlled as to time by the timer 502 and at this time the blower motor 140M is operated so that the blower 140 blows heated and filtered air into the whirler housing 100 as described. The drying cycle is initiated under control of the cam switch CS-11 which has the common and normally closed contacts thereof connected respectively by wires 630A and 629A to the starting contacts of the timer 502. These starting contacts are connected by wires 729A and 730A to contacts 502-1 that are normally open and are cam operated to close circuit from line wire L-2 to one terminal of the motor 502M. The other terminal of the motor is connected to line wire L-1. The closure of the contacts 502-1 provide a running circuit for the timer. Normally open contacts 502-2 of the timer are also closed by an associated cam to close circuit to the blower 140M and

this circuit is mounted for the desired time cycle established in the timer 502. When the switch 502-2 is closed, an energizing circuit is also established to the operating coil of the control relay 502R so that the normal running circuit to the motor of the timer 500 is broken and the timer 500 is thus stopped. During the drying cycle however, the timer 500 runs through its idle or run-out period as previously described.

When the drying cycle has been completed and the contacts 502-2 are opened, and the relay 502R is released so as to re-establish the motor circuit for the timer 500 which again assumes control of the automatic operation of the machine. Thus in the further operation of the timer 500, the speed control cam switch CS-12 that has been closed during the entire drying period, including the idle running period of the timer 500, is opened so that the solenoid valve SV-105 is closed. The air cylinder AC-105 then moves the speed control lever gradually toward its zero position so that the speed of the whirler table is gradually reduced. When the speed control lever 128L is quite close to its zero position, it operates the switch S-128 so as to close this switch. This operates the air valve SV-131 so that the locking plunger 131 is urged toward its locking position, and at this time, of course, the table is rotating at an extremely slow speed. When one of the notches 130N moves into position opposite the locking plunger 131, the locking plunger moves into its locking position so as to stop the table 105 in its desired rotative position. As the locking plunger 131 moves into the notch it operates the switch S-131 so as to break the running circuit to the whirler motor starter 127S, thus to stop the whirler motor 127. The opening of the starter 127S serves to again start the timer 500.

Keeping in mind that lid actuating means are under the same control as the whirler motor 127, it will be evident that the solenoid valve SV-108 is then operated to cause the whirler lid or cover 108 to be moved toward its open position.

When the lid 108 reaches its open position, it operates the switch S-108 so that the station IV selecting circuits are conditioned for control by the cam switch CS-13 which is then closed by the timer 500. Such closure of the cam switch operates the station IV selecting circuits as hereinbefore described so that the head 408 moves into position over the whirler table. When this has been done, the pickup control switch CS-14 is closed so that the head 408 moves down, picks up the plate P from the whirler table 105, and returns it to its upper position in the manner hereinbefore described.

The cam switch CS-15 is then closed so as to select station II in the manner hereinbefore described, and the head 408 moves around in a counterclockwise direction to station II.

The head 408 is then operated through its drop cycle by closure of cam switch CS-16 and this drop cycle is performed in the manner hereinbefore described.

The head 408, of course, returns to its upper position, and the cam switch CS-33 is operated by the timer 500 soon thereafter so as to break the running circuit to its operating motor 500M so that the timer is stopped, and this concludes the automatic cycle.

TYPICAL AUTOMATIC CYCLE

In Fig. 13 of the drawings the timing of a typical automatic coating and drying cycle has been illustrated in the form of a timing chart, and this illustrates the operating times and movements of the principal elements of the installation in a cycle wherein the new plate P that is to be coated is picked up at station I, transported to station IV and deposited on the whirler table 105, after which the lifting and transporting unit moves its lifting head to station III where it remains during the flushing, coating and drying operations that are performed automatically by the whirler as illustrated in such timing

chart. Upon the conclusion of the drying cycle, the lifting and transporting unit 22 returns the head thereof to station IV, picks up the coated plate, using the dry or clean cups 410D so as to avoid contamination of the finished coated surface, and transports the finished plate to station II where it is deposited on top of a stack of finished, coated plates. The head of the lifting and transporting unit then returns to its raised position to terminate the cycle, and the unit 22 remains in this condition until another automatic cycle is initiated.

CONCLUSION

From the foregoing description it will be apparent that the present invention provides an improved whirler in which the drying action is attained in such a way that uniformity of drying is assured and a perfect surface is provided in the coating. The present invention also accomplishes the drying operation in such a way that the circulation of dirt within the whirler housing is minimized or eliminated so that there is no tendency of such circulating dirt or dust to mar the surface of the plate. It will also be apparent that the present invention enables plates to be coated in a uniform manner in that the coating is applied in the same way and in the same amount in each coating operation, and it will also be apparent that the uniformity of application and drying of the coating insures uniformity of the final product.

It will also be evident from the foregoing description that the present invention provides a whirler that is adapted to be started and stopped automatically, and to perform its functions without the attention of an operator, and further it will be apparent that the whirler table is, under the present invention, stopped in such a way that the completed plate is located in a particular relationship in a rotative sense so that the whirler may be closed by a cover of maximum size, and so that the whirler is thereby adapted for mechanical or automatic loading and unloading.

It will also be apparent that the present invention provides a novel lifting and transporting device whereby the plates may be handled and transported to and from a whirler or the like in a simple manner, and this is accomplished in such a way that the lifting force may be applied to the completed plates by engagement with the coated surface. It will also be apparent that the present lifting and transporting apparatus is operable to lift plates from or deposit the same on stacks of varying heights and this is accomplished by control means of an extremely simple and advantageous character.

It will also be apparent that the present invention enables the entire lifting, transporting and coating procedures to be performed automatically and without the attention of an operator after the sequence of operations has been initiated.

Thus while I have illustrated and described a preferred embodiment of my invention it is to be understood that changes and variations may be made by those skilled in the art without departing from the scope of the appending claims.

I claim:

1. In a whirler, a horizontal whirler table, a housing enclosing the table including a top access opening and a cover for closing the same, means for circulating drying air through the upper portions of said housing, an arm mounted on a vertical axis adjacent the edge of said table and swingable from a retracted position within the housing and outwardly beyond said access opening to an operating position wherein one end of the arm is located over the center of the table, and independent supply lines for water and coating material and a valve carried on the end of the arm supplied by said lines and having a discharge nozzle in position to be disposed over the center of the table when said arm is in said operating position and through which water or coating material may be discharged selectively under control of the valve.

2. In a whirler, a horizontal whirler table, a housing enclosing the table including a top access opening and a cover for closing the same, means for circulating drying air through the upper portions of said housing, an arm 5 mounted on a vertical axis adjacent the edge of said table and swingable from a retracted position within the housing and outwardly beyond said access opening to an operating position wherein one end of the arm is located over the center of the table, independent supply lines carried 10 by said arm for water and coating material and a valve carried on the end of the arm supplied by said lines and having a discharge nozzle through which water or coating material may be discharged selectively under control of the valve, and control means for said valve carried by 15 said arm.
3. A whirler as defined by claim 2 having means for swinging said arm between said positions, means controlling said valve to supply coating to said nozzle for a predetermined time period and at a predetermined feeding 20 pressure, and means operable at the conclusion of said period to return said arm to its retracted position.
4. In a whirler, a horizontal whirler table, a housing enclosing the table and having an upper wall with an access opening and a pivoted door for closing said opening, power means for causing opening and closing of the door, drive means for said table, and means coordinating said drive means and said power means to close the door during whirling operation of the table and to open the door at the conclusion of such whirling operation.
5. A whirler according to claim 4 in which coating supply means is provided within said housing and is coordinated with said drive means and power means to supply coating for a limited period while said cover is closed.
6. A whirler as defined in claim 4 in which a coating supply means is movably mounted within the housing for movement between retracted and operating positions located respectively near the edge and near the center of the table, and in which said supply means has power shifting means and power control means for the coating flow coordinated with said drive means to supply coating to the center of the table while the cover is closed and to then withdraw said supply means to said retracted position.
7. A whirler according to claim 6 wherein water supply means are connected to said coating supply means and said power control means are operated after the coating supply means has returned to its retracted position to operate said water supply means and flush a portion of the coating supply means.
8. A whirler according to claim 4 in which liquid supply means within the housing has both water and coating supply means and is moved to a centered relation over the table when the cover is closed and in which a valve forming part of said liquid supply means includes a screened discharge nozzle and is operated to feed flushing water and then coating material to a plate carried on the table.
9. A whirler according to claim 4 wherein said shiftable coating supply means includes water and coating supply lines and valve means for controlling the same, and in which such means is shifted from an outer position near the edge of the table to a central operating position over the table, and in which means are provided for controlling the valve means to supply flushing water and then coating material after said means are in operating position.
10. In a lifting and transporting apparatus, a carrier 70 movable between a plurality of stations, a head vertically movable on said carrier, two sets of vacuum cups on said head, one set being stationary and the other set being shiftable between retracted relation and an effective relation below the level of the stationary cups, selecting means 75 for raising and lowering said other set to render said sets

selectively effective, and selecting means for connecting a vacuum source to the effective set of cups.

11. In a lifting and transporting apparatus, a carrier movable between a plurality of stations, a head vertically movable on said carrier, two sets of vacuum cups on said head, one set being stationary and the other set being shiftable between retracted relation and an effective relation below the level of the stationary cups, selecting means for raising and lowering said other set to render said sets selectively effective, selecting means for connecting a vacuum source to the effective set of cups, actuating means for moving said carrier between said stations, control means for initiating movement of the carrier to any selected station, lifting means for raising and lowering said head, governing means for said lifting means for initiating a pickup cycle of said head, and means at certain of said stations cooperating with said governing means to cause operation of said selecting means.

12. In a plate lifting and transporting unit, a lifting head having vacuum means thereon for holding a plate or the like on the bottom of the head, a carrier having a vertical air cylinder thereon for raising said head, movable support means for said carrier for moving said carrier in opposite directions along a predetermined path between a plurality of stations, reversible actuating means for said support means, electrical control means for said actuating means including station-selecting switches allocated to the respective stations and position-indicating switches to indicate the station at which the carrier is located, and said indicating switches cooperating with any actuated one of said selecting switches to determine the direction of operation of and to initiate operation of said drive means for moving the carrier to the selected station and acting selectively to terminate such movement at the selected station, and control means governing said air cylinder for lowering and raising said head.

13. A unit according to claim 12 in which means operated by said head are operable to disable said position indicating switches when said head is out of its uppermost position.

14. In a plate lifting and transporting unit, a lifting head having vacuum means thereon for holding a plate or the like on the bottom of the head, a carrier having a vertical air cylinder thereon for raising said head, movable support means for said carrier for moving said carrier in opposite directions along a predetermined path between a plurality of stations, reversible actuating means for said support means, electrical control means for said actuating means including station selecting switches allocated to the respective stations and position-indicating switches to indicate the station at which the carrier is located and said indicating switches cooperating with any actuated one of said selecting switches to determine the direction of operation of and initiate operation of said drive means for moving the carrier to the selected station acting selectively to terminate such movement at the selected station, control means governing said air cylinder for lowering and raising said head, locking means for holding said support means in any one of said stations, and means operated by said locking means and effective to disable said control means while said locking means are unlocked.

15. In a plate lifting and transporting unit, a lifting head having vacuum means thereon for holding a plate or the like on the bottom of the head, a carrier having a vertical air cylinder thereon for raising and lowering said head, movable support means for said carrier for moving said carrier in opposite directions along a predetermined path between a plurality of stations, reversible actuating means for said support means, electrical control means governing said air cylinder for lowering and raising said head, locking means for holding said support means in any selected station, means operated by said locking means to disable said control means when said locking means are unlocked, and means governed by vacuum in said

vacuum means and forming part of said control means and effective to initiate raising movement of said head.

16. In a work handling and transporting apparatus, a head having vacuum means for supporting a work piece on the head, carrier means supporting the head for vertical movement for picking up or depositing work pieces and also supporting said head for horizontal movement between a plurality of stations, locking means for locking said carrier means in any of said stations, vertical actuating means for said head, pickup control means for initiating a pickup cycle of said head in which downward movement of said head brings the vacuum means into contact with a work piece, means disabling said pickup control means when said locking means is unlocked, and means governed by establishment of vacuum in said vacuum means to initiate return movement of said head to an upper position.

17. In an apparatus for coating lithographic printing plates, a whirler unit having a closed housing with a rotatable horizontal whirler table therein and a power operated lid forming part of said housing and adapted to be opened for placing a plate on or removing the same from said table, rotative drive means for said table operable to gradually accelerate and decelerate the table, means for stopping the table with its plate positioned in a predetermined relation to the lid, shiftable means movable from a laterally retracted position to an effective position for applying coating material centrally on a plate on said table, blower means for circulating drying air through said housing over such a plate, a plate lifting and transporting unit comprising a head having vacuum means thereon for engaging and lifting a plate, carrier means supporting said head for vertical movement, said carrier being movable horizontally between a plurality of stations one of which constitutes a whirler station at said whirler table and the others of which are located outside of said housing and which include work supply and finished work stations, power means for moving said carrier horizontally from station to station, station selecting means governing said power means and operable to initiate operation of the power means to move said carrier horizontally to any selected one of said stations, vertical operating means for raising and lowering said head, and control means for said units operable in succession to operate the station selecting means to cause movement of said carrier horizontally to said supply station to initiate a pickup cycle of said head at said supply station, to operate said selecting means to cause movement of said head horizontally to one of the other stations, to initiate operation of said table and closure of said lid, to initiate a cycle of application of coating material, to initiate a timed cycle of operation of said blower means, to stop said table and cause opening of the lid, to return said head horizontally to said whirler station and then pickup the coated plate from said whirler, and to operate said selecting means to move said head horizontally to said finished work station, and initiate a drop cycle in which the coated plate is deposited at said finished work station.

18. In an apparatus for coating lithographic printing plates, a whirler unit having a closed housing with a rotatable horizontal whirler table therein and a power operated lid forming part of said housing and adapted to be opened for placing a plate on or removing the same from said table, rotative drive means for said table operable to gradually accelerate and decelerate the table, means for stopping the table with its plate positioned in a predetermined relation to the lid, coating applying means for applying coating material centrally on a plate on said table, means for circulating drying air through said housing over such a plate, a plate lifting and transporting unit comprising a head having power operated attaching means thereon for engaging a plate to attach the same to the head, carrier means supporting said

head for vertical movement, said carrier being movable horizontally between a plurality of stations one of which constitutes a whirler station at said whirler table and the others of which are located outside of the housing and which include work supply and finished work stations, power means for moving said carrier horizontally from station to station, station selecting means governing said power means and operable to initiate operation of the power means to move said carrier horizontally to any selected one of said stations, vertical operating means for raising and lowering said head, and control means for said units operable in succession to operate the station selecting means to cause movement of said carrier horizontally to said supply station, to initiate a pickup cycle of said head in which the plate is deposited on said table, to operate said selecting means to cause movement of said head horizontally to one of the other stations, to initiate operation of said table and closure of said lid, to initiate a timed cycle of operation of said coating applying means, to initiate a timed cycle of operation of said blower means, to stop said table and cause opening of the lid, to return said head horizontally

15

20

5 to said whirler station and then pick up the coated plate from said whirler, and to operate said selecting means to move said head horizontally to said finished work station, and initiate a drop cycle in which the coated plate is deposited at said finished work station.
